UNITED STATES PATENT OFFICE.

CLARENCE P. CHAMBERLIN, OF BIRMINGHAM, MICHIGAN.

WINDSHIELD AND HINGE THEREFOR.

1,338,487.

Specification of Letters Patent. Patented Apr. 27, 1920.

Application filed December 29, 1916. Serial No. 139,626.

To all whom it may concern:

Be it known that I, CLARENCE P. CHAMBERLIN, a citizen of the United States, residing at Birmingham, county of Oakland, 5 State of Michigan, have invented a certain new and useful Improvement in Windshields and Hinges Therefor, and declare the following to be a full, clear, and exact description of the same, such as will enable 10 others skilled in the art to which it pertains to make and use the same, reference being had to the accompanying drawings, which form a part of this specification.

This invention relates to windshields for 15 vehicles more particularly to that type in which the sash and frame supporting the same is not truly rectangular in form. In the modern type of automobile body, it has been found desirable more particularly for 20 the sake of design to make windshields less in width at the bottom than at the top more nearly conforming to the width of the hood or cowl at the bottom and widened at the upper end to correspond to the width of the 25 vehicle top at the point of union with the wind-shield frame which is considerably wider than the cowl by reason of the shield being positioned at an angle thereto. In other forms of windshields, particularly 30 what is known as the V type lately used on inclosed cars, the windshield is irregular in form one side member thereof oftentimes being positioned at a right angle to the horizontal members and the opposite side positioned at an angle thereto. With either 35 type of frame mentioned a common expedient has been to hinge the windshield at the upper edge which results in an undesirable type of hinge.

The present invention seeks to provide a 40 hinge for irregularly shaped windshields adapted to support the side members of the shield in the contiguous side frame members and one that is universally adaptable 45 for use with frame and windshield side members of any degree of angularity one to the other or to a perpendicular. A further object is a windshield hinge adapted for use upon opposite side bars of a windshield, the 50 hinges being similar in form irrespective of angularity of the sash or frame members and adapted to allow the sash to swing about a horizontal axis.

A further object is a simple and inexpensive hinge member adapted to be used with frames of various angles as mentioned, and

adapted to be used with sash and contiguous frames that are out of parallelism without necessity of accurately squaring the side frame with the contiguous shield member 60 and further object is a hinge of the character stated that is neat in appearance, inexpensive in construction that is readily and easily manipulated to maintain the shield at any desired angle relative to the frame. 65 These objects and the several novel features of the invention in its preferred form are hereinafter more fully described and claimed and shown in the accompanying drawings in which— 70

Figure 1 is a geometrical elevation of the lower part of an irregularly shaped windshield and supporting frame therefor showing my improved hinge.

Fig. 2 is an enlarged view of the hinge, 75 a portion thereof removed to show the interior construction.

Fig. 3 is a side elevation partly in section of the hinge bearing and binding member taken on line $x-x$ of Fig. 2. 80

Similar characters refer to similar parts throughout the drawing and specification.

As shown in Fig. 1 the windshield is provided with side bars 1 and 2 and is provided with upper and lower sections 3 and 85 4 similar in form. It is to be understood, however, that the hinge is adapted for use with windshields formed of one or several sections as may be desired. The frame 5 surrounding the shield sections is similar in 90 form and in either type of windshield, the section or sections turn about the horizontal axis indicated by the dotted line $a-a$ in Fig. 1. On account of the angularity of the side bars 1 and 2 and contiguous frame, 95 the hinge member on each side of the section is formed of a ball member 6 and a socket member 7 indicated more clearly in Fig. 2. The ball member 6 is provided with a base 8 adapted to be secured to the bar 100 or sash of the windshield. The line c through the center of the ball and of the base being at a right angle to the sash of the shield, thus lies at an angle to the axis of the rotation of the section indicated by the dotted line b in Fig. 2. It is to be noted 105 that the line c through the center of the ball and base may occupy various positions or lie at various angles to the axis of rotation b with equal facility by reason of the ball being capable of being turned to a considerable extent in the socket 7. Thus the 110

frame 5 need not necessarily lie parallel with the shield frame 1 and the necessity for accurate work in the positioning of the frame and shield members is avoided.

5 The socket 7 is formed of two parts, a base 9 and cap 10 located in a recess in the frame 5. Both the cap and base are correspondingly shaped to receive the ball, the circumferential wall of the aperture being 10 V shaped in form as will be understood from Fig. 2. The ball is thus engaged at two circumferential lines 11 and 12, the center part of the point or V being greater in diameter than the ball and thus out of contact therewith. By this arrangement the ball is held from lateral movement in the socket and the contacting wall of the aperture provides a means for frictionally holding the ball from rotation in the socket. For this purpose 15 the cap member 10 is provided with a screw 13 securing it to the base 9 and a binding screw 14 on the opposite side of the ball by means of which the cap may be brought tightly into engagement with the ball to 20 bind it in the socket, the cap at the lower end being out of contact with the base member as indicated at 15. By relieving the screw 14 the ball may be loosened in the socket and the windshield section readily 25 turned about an axis indicated by the line a—a in Fig. 2 drawn through the centers of the two balls. By reason of the arrangement of the ball and socket shown, the ball may rotate in the socket on an axis coinciding 30 with the axis of rotation of the frame although the axis of the ball and base may lie at various angles to the axis of rotation of the frame. The ball thus has a peculiar motion in the socket rotating in a plane at 35 a right angle to the axis of rotation of the section and may also turn in the socket on an axis at a right angle to the axis of rotation. To illustrate—in Fig. 2 the point indicated by the arrow 20 is in contact with 40 one edge of the socket. On forward rotation of the windshield section 1, this point will turn on a line at a right angle to the line b and on being turned half way around the point 20 will be inside the line of contact 45 with the edge of the socket indicating a movement of the ball relative to the socket about an axis perpendicular to the plane of the drawing, whereas, if the sash were turned about the axis c at an angle to the horizontal the point 20 would remain in contact with the edge 12 throughout the entire revolution.

50 From this description it will be understood that it is wholly unnecessary for the 60 socket 7 to be positioned exactly parallel with the sash bar in order that the joint may work with proper freedom and the

hinge is thus adaptable for use with frames lying at various angles without necessity of any special provision being made to accommodate the particular angle of the section bars and the frame. The hinge will also operate equally as well with frame and sash members at a right angle to the axis of rotation as at any other possible angle.

65 With a hinge joint constructed substantially as shown and described and having the described universality of action, a manufacturer of hinges or hinge joints for windshields may make a single form of hinge 70 joint adaptable for use with all the various designs of windshield sections and frames, and thus the cost of manufacture is lessened to a very material degree enabling the manufacturer to make a standard article 75 universally adapted for indiscriminate use with shields and frames of various designs.

80 Having thus briefly described my invention, its utility and mode of operation, what I claim and desire to secure by Letters Patent of the United States is—

85 1. In a wind shield, a shield section having side bars positioned at an angle other than a right angle to the top and bottom bars thereof, a frame for the section having 90 side members parallel respectively to the contiguous side of the section, a socket in each frame member, a ball member secured to each side bar and seating in the respective socket, the axis of the ball and support being at a right angle to the side bars of the section and at an angle to the turning axis of the section.

95 2. In a wind shield, a shield section having side bars positioned at an angle relatively one to the other, a frame for the said section having similarly positioned side members, a ball having a base secured to each side bar of the section and extending at a right angle thereto, a socket for each ball in the respective side member of the frame, the section swinging about an axis passing between the centers of the two balls, the longitudinal axis through the ball and base being at an angle to the swinging axis 100 of the section.

105 3. In a wind shield, a shield section having side bars positioned relatively at an angle one to the other, a frame member for the said section having similarly positioned side members, a ball having a base attached to each side of the section, a socket for the ball in each side frame, the longitudinal axis passing through the center of each ball, and means for releasably binding each ball 110 in its socket.

115 In testimony whereof, I sign this specification.

CLARENCE P. CHAMBERLIN.
